Montgomery Ferar, Royal Oak, Mich., assignor to Seeger
Refrigerator Company, St. Paul, Minn., a corporation
of Minnesota

Application October 15, 1953, Serial No. 27,181

Term of patent 7 years

(Cl. D67—3)

To all whom it may concern:

Be it known that I, Montgomery Ferar, a citizen of the United States of America, residing at Royal Oak, in the county of Oakland, State of Michigan, have invented a new, original, and ornamental Design for a Refrigerator Cabinet, of which the following is a specification, reference being had to the accompanying drawing, forming a part thereof.

Fig. 1 is a front perspective view of a refrigerator cabinet embodying my new design.

Fig. 2 is a side elevational view thereof.

Fig. 3 is a top plan view thereof.

Fig. 4 is a fragmentary cross sectional view taken on line 4—4 of Fig. 2.

The side of the cabinet not shown is similar in appearance to the side in view.

The essential features of my design reside in the portions shown in full lines.

I claim:

The ornamental design for a refrigerator cabinet, as shown and described.
